ACCOUNTING MACHINE

Thomas J. Watson, New York, N. Y., assignor to
 International Business Machines Corporation,
 New York, N. Y., a corporation of New York

Application July 15, 1943, Serial No. 494,819

3 Claims. (Cl. 235—61.9)

1

The present invention relates to accounting and statistical machines and more particularly to machines for performing problems relating to restaurant accounting, such as involve food control and billing.

One of the objects of the invention is to provide a record card upon which data in the form of a menu are preprinted, and upon which card the patron may graphically record his selections in designated positions or areas adjoining the listed items of the menu. Such a card is provided with printed headings and general item designations, and in spaces provided therefor the menu for a particular day or period may be mimeographed or printed together with the individual prices in accordance with prevailing custom. Such card, when so selectively marked by the patron, becomes a permanent original record from which the waiter may be guided in attending to the patron's desire, and such card will subsequently serve as a bill or check.

A further object of the invention is to provide a machine in which the record card as marked by the patron is inserted. Such machine contains mechanism which senses the marks, and in accordance with a preset price schedule set up in the machine controls accumulating, punching, and printing apparatus to automatically punch into the card the unit prices of the items ordered, together with the total price thereof. This total is also printed on the face of the card in a predetermined position. The machine is further provided with a plurality of counters, one for each marking position of the card, and such counters are controlled concurrently with the other mechanism to count the number of each different item ordered during the day or other period.

At the end of the day there accordingly will have been collected a group of cards, one for each patron, prepared in the desirable form of a file of perforated record cards which may thereafter be employed in sorting, printing, billing and other statistical machines, through the use of which an analysis or inventory may be rapidly and automatically obtained.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a view showing the general appearance of the machine.

2

Fig. 2 is a facsimile of a record card with data thereon arranged to represent a menu.

Fig. 3 is a transverse section of the machine taken generally along the lines designated 3—3 of Fig. 1.

Fig. 4 is a similar section of the machine taken along the lines 4—4 of Fig. 1.

Fig. 5 is a view of the accumulating mechanism.

Fig. 6 is a detail view of one of the readout commutator devices, the view being taken along lines 6—6 of Fig. 5.

Fig. 7 is a plan section taken on lines 7—7 of Fig. 3, showing the arrangement of the mark sensing devices.

Fig. 8 is a plan section taken substantially along lines 8—8 of Fig. 3, showing the cross connections between the total punching and printing mechanism.

Fig. 9 is a sectional view taken along lines 9—9 of Fig. 5, showing a part of the accumulator resetting device.

Fig. 10 is a chart showing the time of operation of various components of the mechanism.

Figs. 11a and 11b placed side by side with Fig. 11b to the right constitute a wiring diagram of the electrical circuits of the machine.

The record card

30 Referring to Fig. 2, the record card R is subdivided into a plurality of areas 2 in which the items of the menu, such as fruit cup, scallops, roast lamb, etc., are printed together with the price thereof. These areas are provided with suitable headings, such as appetizer, soup, etc., and across the top of the card is provided space for the accommodation of date, table, signature of the customer where the service is to be charged, etc. In each area 2 there is provided a block 3 in which the customer is to draw a line with a pencil or other electrically conductive medium to represent his choice of items on the menu. At the right end of the card there is provided a field 4 containing four vertical columns of so-called index point positions designated 0 to 9, in which the machine will record a total by perforations in appropriate positions.

An area 5 is also provided in the upper right hand corner in which a total is to be printed by the machine. A further column 6 is provided in which classification data, such as waiter number, may be preperforated. The length of the card is subdivided into eighty columns indicated by the lines 7 across the bottom of the card, 55 and in these columns the machine will perforate

the individual prices of those items that have been ordered by marking.

The procedure is briefly as follows. The customer is presented with a card R upon which there appears only the printed data and the classification hole in column 6. On this card he makes his selection by marks, as shown in several of the spaces 3. From this marked card the waiter serves the desired items, and at the termination of the service the marked card is placed in the machine which will punch therein perforations representing the prices of the items ordered as, for example, perforations representing 15 cents are made in the first two columns of the card, and perforations representing 10 cents are made in the fifth and sixth columns. In field 4, perforations representing the total bill are made and the total is printed in area 5.

The machine

Car feeding mechanism.—Referring to Figs. 1 and 3, the record card R is inserted in the opening 79 of the machine and thereupon driven by a pair of constantly rotating rollers 71, which rapidly advance it to the second pair of rollers 72 and against a stop or shutter 73, which latter locates the card in mark sensing position with the rollers 71 and 72 slipping on the card after its movement is interrupted by the shutter. While in this position, the card is sensed and thereafter shutter 73 is rocked out of the path of the card, so that the rollers 71, 72 resume feeding to advance the card to subsequent pairs of rollers 74, 75 which convey it against a second stop or shutter 76 which locates the card in punching and printing position.

After punching and printing have been effected, stop 76 is rocked out of the path of the card and rollers 75 advance it to further rollers 76, which convey the card through a chute 77 into a tray 78 (see Fig. 1) from which it may be removed by the operator. Rollers 71, 72, 73, 74, 75 and 76 are interconnected by gears generally designated 79 in Fig. 4, one of which through an idler 80 is driven by a gear 81 free on a shaft 82. This gear is in constant rotation being driven by any suitable means, such as an electric motor, so that as long as the motor is in operation the feed rollers continue to operate.

Mark sensing mechanism.—With the card R in position against stop 73 (Fig. 3), the marking areas 3 are positioned opposite sets of sensing pins designated 83a, 83b, 83c (see Fig. 7) which are mounted in an insulating block 86. On the opposite side of the card is located a pressure plate 84 of resilient material which is mounted for horizontal reciprocation through rollers 85 carried by the plate and stationary guide members 86. Rocking of the rod 87 will straighten toggle links 88 and force the plate 84 toward the left as viewed in Fig. 3, to press the record card and the marks thereon against the ends of pins 83a, 83b, 83c. In the positions in which there is a mark, the mark will form an electrical connection across the three pins to establish electric circuits, which will be explained in connection with the circuit diagram.

Card lever contacts.—Located in the path of the card (Fig. 3) is a card lever 90 which is engaged by the card as it moves downwardly and is rocked about its pivot 91 to close a pair of contacts designated CL as shown in Fig. 3.

Operating clutch mechanism.—At the front of the machine (Figs. 1 and 4), there is provided a button 92 which, when pressed, will slide a bar 93

toward the right, and through slots 94 cooperating with fixed pins 95 this movement toward the right will be accompanied by downward movement for a purpose presently to be explained. Resiliently pivoted on bar 93 is a finger 96 which upon movement of the bar will rock a clutch lever 97 pivoted at 98. The upper end of the lever normally engages a dog 99 pivoted at 100 to arm 101 which is secured on the shaft 82. Integral with the constantly turning gear 81 is a clutch element 102 which is accordingly in constant rotation. Upon rocking of lever 97, dog 99 is released for engagement with element 102, so that the arm 101 and shaft 82 are thereafter driven with the gear 81. Also secured on shaft 82 are several cams for operating the various mechanisms. Cam 103 cooperates with a bell crank follower arm 104 pivoted at 105, and through pin and slot connection 106 rocks a lever 107 on the end of shaft 87, thereby moving the pressure plate 84 of Fig. 3 toward the left.

Referring to Fig. 4, when button 92 is pressed, it will release the clutch and, after doing so, latch 96 will snap beneath the lower end of lever 97, so that it may rock back into its initial position under the influence of its spring to reengage dog 99 and uncouple the parts after the cams have made a single revolution.

Shutter operating mechanism.—Referring to Fig. 3, shaft 82 has secured thereon a pair of cams designated 108, 109 and which operate a pair of like levers 110 located one behind the other in Fig. 3. The lever 110 operated by cam 108 rocks rod 111 upon which shutter 76 is mounted to rock the shutter out of the path of the card at the time determined by the configuration of the cam. Arm 110 operated by cam 109 is loose on the rod 111 and has a link connection 112 with an arm 113 secured to a rod 114, upon which the upper shutter 73 is mounted, and the time of operation of this shutter will be in accordance with the configuration of cam 109. Reference may be had to Fig. 10 wherein the time of operation of the cams is indicated.

The punches.—When the card is in position against the lower stop 76, it lies between a die 115 and a plurality of punches 116 arranged in eighty columns across the length of the card and ten rows arranged vertically, the spacing being in accordance with the spacing of the hole positions on the record card. For each vertical column of punches 116 there is a vertical slideable bar 117 provided with teeth 118 and a spring pressed interposing plunger 119. The manner in which this bar is reciprocated is as follows: In Fig. 4 a cam 120 secured to shaft 82 rocks follower arm 121 on shaft 122 which in Fig. 3 rocks a bail 123 clockwise and through springs 124 urges levers 125 (there being one lever for each card column) in the same direction. The forked end of each lever 125 engages a pin 126 in bar 117, so that the bar is elevated and the plunger 119 passes the ends of punches 116 in succession. The bar may be interrupted with the plunger 119 opposite any of the punches and, when so interrupted, bail 123 will continue through its invariable excursion, with spring 124 extending. The means for stopping the bar in any position comprises a stopping latch 127 which is normally latched in the position shown (Fig. 3) by the armature 128 controlled by a magnet 129.

Upon energization of the magnet, the latch is released to engage a selected one of the stops 118. After the bar has been positioned, a punch 75 frame 130 suitably mounted for horizontal recip-

location by means of rollers 131 and guides 132 is moved toward the left to force plunger 119 against the selected punch 116 and force the punch through the card into the die 115. The mechanism for reciprocating the frame 130 comprises a cam 133 (Fig. 4) which rocks a follower arm 134 on shaft 135, which in turn through toggle links 136 effects the reciprocation of the frame. The punches are suitably notched as shown in Fig. 3 for cooperation with the usual stripper bars 137 which are tied together by a plate 138 which has pin and slot connection 139 with frame 130, so that as the frame moves toward the left the stripper bars 137 will be free for movement in the same direction and, when the frame returns, the bars 137 are drawn toward the right to retract the punches from the card. When the punch bars are moved downwardly, a camming portion 139a at their upper ends will engage stop pawls 127 and effect relatching thereof on armature 128.

Total indicating mechanism.—Referring to Figs. 3 and 8, the four punch interposer bars 117 aligned with the four columns of the card R in which the total amount is punched are provided with teeth 140 which, as these bars are positioned, rotate related gears 141 which through nested sleeves 142 drive gears 143. These in turn through sets of idler gears 144 and 145 drive gears 146, which through further nested sleeves 147 drive gears 148 which mesh with teeth in vertically extending bars 149. These bars are provided with teeth at their upper ends (Fig. 3 and Fig. 4) which mesh with gears 150 affixed to indicating wheels 151, which are visible through an opening 152 in the casing of the machine (Fig. 1). Through the connections traced, positioning of any of these four bars 117 to represent a digit is accompanied by like positioning of the related indicating wheel 151 to display the digit selected at the opening 152.

Total printing mechanism.—Each bar 149 (Figs. 3 and 8) has a lateral extension 153 intermediate its ends. This extension is provided with teeth meshing with a gear 154 integral with a printing wheel 155, so that the printing wheel will be rotated together with the indicating wheel 151 to present the appropriate type face to a horizontal printing line opposite a platen 156. This platen is carried by a bracket 157 (Fig. 3) secured to the punch frame 130 so that, when the frame moves toward the left, the platen will press the card against the type wheel to effect an impression through a suitable inking ribbon indicated at 158.

Accumulating mechanism.—The accumulating mechanism employed in the present machine is of the construction shown and described in detail in Patent 1,914,272 of R. J. McFall granted June 13, 1933. The same will be but briefly described, and to facilitate reference to such patent like parts will be identified with the same reference characters as employed in the patent.

Referring to Fig. 5, the accumulator comprises a plurality of gear trains, one train for accumulating units digits, another train for the tens digits, etc. These gear trains are supported in a plurality of fixed parallel frame members 16, and the various units of the two trains illustrated are designated A, B, C, D and A', B', C', and D' respectively. Each of the units A or A', for example, comprises a large gear 17 serving as a planetary gear carrier loosely mounted for rotation upon a fixed stub shaft 18 secured in frame 16. Secured to the inner end of shaft 18 is a

sun gear 20 constituting one member of a differential mechanism. Secured to the face of gear 17 is a pair of bracket arms 21 which support a shaft 22 on which are journaled planetary gears 23, 24 meshing with sun gear 20 and also with a gear 25 similar to gear 20, which gear 25 is fixed to the shaft 26 journaled in the next frame 16. The gear 17 of the next unit B or B' is mounted for free rotation on shaft 26, while the sun gear 20 of such unit is rigidly secured to said shaft. The same is true for the succeeding units C, C' and D', no differential mechanism being employed at unit D. It will be seen that the gear 25 of the differential mechanism C is secured to a shaft 26X which carries a transfer wheel 35 having on its periphery a cam flange 36 for the purpose of carrying over from one gear train to that of the next higher order. Whenever wheel 35 makes a complete revolution, cam 36 causes positive engagement of the clutch at a particular point in the rotation of wheel 35 and a spring thereafter effects declutching. With the cam rotating at its slowest rate, the period of engagement would be determined by the cam 36. At higher rates, the clutch lever would not necessarily follow the cam contour but would depend on the period of the spring to declutch it and, if desired, a positive knockout for the clutch would be provided so that the clutch, whenever engaged, at whatever speed would remain engaged for only one step of advance.

Extending through and journaled in the frame members 16 is a pair of shafts 37 and 37' of which shaft 37' is driven by suitable gear connection (not shown) from the shaft 82 of Fig. 4, so that this shaft rotates when shaft 82 is coupled for operation. Shafts 37 and 37' and similar shafts of higher denominational orders are interconnected through suitable chain and sprocket connections 39, so that corresponding shafts in all orders will be rotated in unison. Mounted freely on each of these shafts adjacent each of the differential mechanisms of each train of gears is a sleeve 40 having formed integral therewith two similar spaced gears 41 and 42. Also carried by the sleeve 40 beyond the gear 42 is a clutch member 43. A similar and cooperating clutch member 44 is slidably mounted on the shaft, but is splined thereto by a key 45. This clutch member 44 has a peripheral groove in which is fitted a yoke 46 carried by an arm 47, the lower portion 48 of which is somewhat flexible and is secured to a fixed support carried by the frame 51.

Adjacent the corresponding magnet such as 8 or 9 is an armature 49 adapted to be attracted by such magnet. The arm structure 47, 48 and associated parts are carried by a movable frame member comprising parallel bars 50 and 51 united at intervals by cross bars 52. Supported between the bars 50 and 51 is a shaft 55 on which is mounted a back gear 56 which is continuously meshing with gear 42. Thus, when one of the magnets 8 or 9 is energized, the clutch members 43, 44 are brought into engagement and the gears 41, 42 and 56 rotate. The movable frame 50, 51 is capable of being shifted laterally by means of a pair of eccentrics 53, 53' carried by a shaft 54. By rotating these shafts 54, the movable frame may be shifted laterally from the position shown in A' to that illustrated at B'. When in the first position, the large gear 17 is in mesh with the back gear 56 and consequently will be driven in one direction by the shaft 37 and, while 75 in the second position, gear 17 is in mesh with

the gear 41, and hence will be driven in the opposite direction.

Each of the arms 47 carries an extension 58 in the nature of a pawl which is adapted to engage and lock the associated gear 42. When the armature 49 is attracted and the clutch members 43 and 44 engage, pawl 58 is shifted to the left out of engagement with the gear 42, thus permitting this gear and associated parts to turn freely. Movement of pawl 58 toward the left will cause the pawl to engage and close a pair of contacts designated 57 for the purpose of maintaining the magnet energized, as will be explained in connection with the circuit diagram.

For the purpose of the present invention, each of the right hand shafts 26X, 26Y and similar shafts of higher orders has secured thereto a brush 160 (see Fig. 6) which will take one of ten positions in accordance with the digital value entered in its related order, and will make contact with segments 161 on a fixed commutator in these ten positions. Also secured to each shaft near its end is a disk 162 which is in frictional contact with a disk 163 loosely mounted on the shaft. The several disks 163 are interconnected by belt and pulley drive generally designated 164, which are operated from a motor 165. Integral with each disk 162 is a notched disk 166 (Fig. 9) in the plane of which there is a stop pawl 167 pivoted at 168. The several pawls 167 are interconnected through a link 169 through spring, pin and slot connection generally designated 170, and the lowermost pivot 168 carries a spring pressed armature 171 of a magnet 172. This mechanism is utilized for restoring or zeroizing the several accumulator shafts, and during the resetting operation magnet 172 is energized to rock the stops 167 against their related disk 166. At the same time motor 165 is operated to frictionally drive the several accumulator shafts in a forward direction. As each wheel arrives at its zero position, the notch is engaged by stop 167 and thereafter the frictional connection between disks 162 and 163 will slip.

Circuit diagram

The complete operation of the apparatus will now be explained in connection with the circuit diagram (Figs. 11a and 11b) to point out the sequence in which the various mechanisms function in accordance with the timing of their operations as represented in Fig. 10.

In Fig. 11a are shown three pairs of manually settable dial switches generally designated 173, comprising fixed contact segments 174 and positionable contact pointers 175. The dial switches in the upper horizontal row are provided with ten segments 174, while the units switches are provided with only two, designated 0 and 5, so that on any pair of switches in a vertical row two place amounts may be set with 5 cent intervals; for example, the left hand pair of switches 173 is set to represent 25, the central pair is set to represent 40, and the right hand pair represents 75. For simplification of the diagram, only three pairs of switches are shown, but it is to be understood that there is a pair provided for each marking area 3 of the card in Fig. 2, and each pair will be adjusted to represent thereon the price or value of the commodity printed in the related card field.

In Fig. 11a are shown two commutator devices designated Emitter A and Emitter B, and in Fig. 11b is shown another such device designated Emitter C. Each of these devices comprises a

plurality of stationary contact segments 176 and a switch arm 177. The arms 177 are secured to the main driving shaft 82 and rotate therewith, while the segments 176 of the emitters are so located in the path of the arms 177 that contact is made at the times designated in the timing chart Fig. 10. Also mounted on shaft 82 are contact operating cams for controlling contacts generally designated C in the circuit diagram, and these contacts are closed at times indicated in Fig. 10.

The machine is also provided with unit counters designated 178 in Fig. 11a which are magnetically operated to count one for each energization of an associated magnet 179. The location of these counters in the machine is indicated in Figs. 1 and 3, where the location of the dial switches 173 is also shown.

As previously explained, upon insertion of a record card in opening 79 (Fig. 3), the constantly running feed rollers will advance it into sensing position against the upper stop 13. The operator now presses the button 92 which will release the one revolution clutch, so that shaft 82 will make one complete revolution and then come to rest. During this revolution, cam 103 first operates to move the pressure plate 84 against the card and sensing pins, so that in positions where marks occur the three related pins are electrically interconnected. When cam contacts C1 (Fig. 11a) close, there will be a circuit completed from positive line 180, wire 181, central contact pin 83b, the pencil mark, contact pin 83c, counter magnet 179, contacts C1 and thence to ground. The energization of magnet 179 will advance its counter one unit. The movement of the card to its sensing position will have engaged the card lever 99 to close card lever contacts CL, so that there is a circuit traceable from line 180, contacts CL and magnet 179 related to a total counter magnet 178, which will advance one unit and accordingly count the number of cards passing through the machine.

Upon the sensing of the mark there is a further circuit traceable from line 180, wire 181, central contact pin 83b, the pencil mark, the pin 83a, wire 182, relay magnet R1 to ground. Magnet R1 will close its contacts R1a and R1b which accordingly will remain closed as long as the pencil mark continues to bridge the sensing pins. Similar circuits for counting marks in other areas and energizing other related R1 relays are completed at the same time. In the circuit diagram, for simplicity the magnets 179 and relays R1 are shown as being directly energized through the pencil marks. In practice, suitable current amplifying devices, as is well known, would be interposed to amplify the current sufficiently to operate the magnets.

At the time indicated in Fig. 10, the brush 177 of emitter A will contact its segments 176 in succession, and a group of wires designated 183 (Fig. 11a) will be connected in succession to line 180 in the order 9, 8, 7, etc. With the switch 175 set at its 2 segment 174, for example, a circuit will be traceable when brush 177 contacts its 2 segment 176 as follows: from line 180, brush 177 of emitter A, the 2 segment 176, the 2 wire 183, one of the wires 184, the 2 segment 174, contact arm 175, wire 185, contacts R1a, wire 186, normally closed contacts R2a, wire 187 (Fig. 11b), adding clutch magnet 9 to ground. The accumulator shafts 37, 37' are geared to the shaft 82, so that the accumulator shafts make one revolution while the commutator brush 177 of emitter A traverses

its segments 176, so that energization of magnet 9 at this time will cause entry of a 2 into the tens order of one of the accumulator units.

Just prior to this, when the brush 177 contacted the 5 segment 176, a circuit was completed from line 180, brush 177 of emitter A, the 5 segment 176, the 5 wire 183, the 5 wire 184, to the 5 segment 174 at the units order switch, thence through contact arm 175, wire 188, contacts R1a, wire 189, normally closed contacts R2b, wire 190 (Fig. 11b) and magnet 8 to ground. Thus, the units order magnet 8 will be energized at a time appropriate for the entry of 5 in the related position. The magnets 8 and 9 close their related contacts 51, so that a holding circuit therefor is provided which is traceable from line 180 (Fig. 11b), wire 191, cam contacts C3 (see Fig. 10), contacts 51, magnets 8 and 9 in parallel to ground. The contacts C3 are timed to open at a so-called zero time, at which time the adding wheels will have advanced the required amount.

During this same period of time, sensing of other marks will have energized others of the adding magnets 8 and 9, so that the accumulator will concurrently receive a plurality of amounts and through the differential adding mechanism described will position the readout brushes 169 of Fig. 11b to represent the total of the entered amounts. As indicated by dotted lines in Fig. 11b, a second accumulator mechanism may be provided if desired, wherein through parallel circuit connections a second set of magnets 8 and 9 may be energized. Such second accumulator would serve as a so-called grand total accumulator and will contain a running total of all amounts entered, while the first accumulator will be reset after each card in the manner yet to be explained.

While the selected amounts are being entered, the punch bars 117 are moved downwardly under control of their cam 120 and then rise again. During the upward movement of the bars, emitters B and C traverse their respective sets of contacts 176 as shown in Fig. 10 and a pair of contacts C2 (Fig. 11a) are closed. Such closure will cause energization of a relay magnet R2 to shift its related contacts R2a and R2b into their alternate positions. Accordingly, as the brush 177 of emitter B now traverses its segments 176, the wires 183 will receive impulses through connecting wires 192, and circuits will now be completed from line 180, brush 177 of emitter B, contact segments 176, wires 192, 183, 184, the segments 174, switch arms 175, contacts R1a, R1b, wires 186 and 189, the upper contacts R2a and R2b and thence through wires 193, and selectively adjustable connections 194 to punch magnets 129 and thence to ground. The brush of emitter B is synchronized with the movement of the punch bars, so that if, for example, a brush 175 is set on a 5 segment, the magnet 129 will be energized at a time to intercept the related bar 117 through its 5 tooth 118 (Fig. 3), to thus position the interposer 119 in line with the 5 punch 116. In this manner the punch bars are concurrently positioned, a pair of each under control of one of the marks and in accordance with the setting of the related switch. At the same time emitter C will complete circuits in Fig. 11b from line 180, brush 177 of emitter C, segments 176, wires 195, wires 196, segment 161, brush 160, wires 197 (Fig. 11a), to other punch magnets 129 and thence to ground.

Through these circuit connections the punch bars associated with the total printing wheels are

concurrently positioned with the punch bars controlled by the marks, and as previously explained the total printing wheels and total indicating wheels will be concurrently adjusted. It is to be noted that printing wheels 155 and indicating wheels 151 are provided only for the four columns of the total field of the card. This is seen from Fig. 8 where only the four end punch interposer bars 117 are geared to gears 141. After the bars have been positioned, the sensing frame 84 is retracted and the upper stop 73 is also retracted, so that the card now advances rapidly to position against stop 76 and, after its arrival there, cam 133 operates to effect punching and printing in accordance with the setting of the bars and wheels. Thereafter, the lower stop 76 is retracted by its cam 109 and the card is fed into the tray 78. While the card is advancing to punching position, cam contacts C5 (Fig. 11b) close to energize the magnet 172 and shortly thereafter cam contacts C4 close to place the motor 165 in operation. This operation is maintained for the interval indicated in Fig. 10 during which the accumulator is reset as explained in the mechanical description.

At the end of the cycle, the shaft 82 comes to rest and it will be noted that in such rest position the punch bars remain in their set position, so that the last previous total continues to be displayed at the window 152 and will remain so set until another cycle of operation of shaft 82 is brought about.

While there have been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In a machine controlled by a record card having a plurality of marking areas thereon in each of which areas a mark may be made to represent a commodity, a plurality of settable switches for each marking area, the switches for each area being settable to represent a selected value for the related commodity, means for sensing the areas of the card, punching mechanism, accumulating mechanism, operating means therefor, means jointly controlled by said sensing means and said settable switches, for controlling the operating means of said accumulating mechanism to obtain therein the total of the values represented by the switches whose related areas contain marks, further means jointly controlled by said sensing means and said settable switches for controlling a portion of said punching mechanism to individually record in the card the values represented by the switches whose related areas contain marks, and means controlled by said accumulating mechanism concurrently with the operation of said last named means, for controlling another portion of said punching mechanism to record in the card the total of said values together with the recording of the individual values.

2. In a machine controlled by a record card having a plurality of marking areas thereon in each of which areas a mark may be made to represent a commodity, a plurality of settable switches for each marking area, the switches for each area being settable to represent a selected

11

value for the related commodity, means for concurrently sensing the areas of the card, punching mechanism, accumulating mechanism, operating means therefor, means jointly controlled by said sensing means and said settable switches, for controlling the operating means of said accumulating mechanism to obtain therein the total of the values represented by the switches whose related areas contain marks, said control being concurrent for all values accumulated, further means jointly controlled by said sensing means and said settable switches for controlling a portion of said punching mechanism to individually record in the card the values represented by the switches whose related areas contain marks, and means controlled by said accumulating mechanism concurrently with the operation of said last named means, for controlling another portion of said punching mechanism to record in the card the total of said values together with the recording of the individual values.

3. In a machine controlled by a record card having a plurality of marking areas thereon in each of which areas a mark may be made to represent a commodity, a plurality of settable

25

12

switches for each marking area, the switches for each area being settable to represent a selected value for the related commodity, means for sensing the areas of the card, punching mechanism, accumulating mechanism, operating means therefor, means jointly controlled by said sensing means and said settable switches, for controlling the operating means of said accumulating mechanism to obtain therein the total of the values represented by the switches whose related areas contain marks, further means jointly controlled by said sensing means and said settable switches for controlling said punching mechanism to individually record in the card the values represented by the switches whose related areas contain marks, printing mechanism, operating means therefor operable concurrently with the punching mechanism, and means controlled by said accumulating mechanism concurrently with the operation of said last named means, for controlling said printing mechanism to print on the card, concurrently with the operation of said punching mechanism, the total of said values.

THOMAS J. WATSON.
